SUCTION SLICE FOR PAPER MAKING
MACHINESKenneth J. Mackenzie, Rochester, N. Y., assignor
or to Eastman Kodak Company, Rochester,
N. Y., a corporation of New Jersey

Application January 16, 1937, Serial No. 120,968

4 Claims. (CL. 92—44)

This invention relates to paper making machines and particularly to slices for controlling the flow of stuff in such machines.

One object of my invention is to provide a slice adapted to remove foam which usually occurs near a slice in the wet end of a paper making machine. Another object of my invention is to provide a slice which will both control the height of stuff passing through a passageway and at the same time will also provide an exit for foam accumulating on the surface of the stuff. Still another object of my invention is to provide a slice in the form of a hollow member or receptacle into which the foam may pass and from which the foam or the foam and stuff may be removed. Other objects will appear from the following specification, the novel features being particularly pointed out in the claims at the end thereof.

In the manufacture of high-grade paper, considerable sizing material is ordinarily used. When the paper stock is flowed onto the making wire, the constant agitation to which the stock is subjected to in flowing through the necessary channels causes considerable foam to rise to the surface, and where an impediment is put in the path of stock, such as a slice, this foam will collect. If the rate of flow of stuff through the machine remains constant, the stuff may flow under the slice without the foam during any particular damage. However, in the normal operation of paper making it is necessary to frequently change the speed of the machine, and also to change the consistency at which the paper stock flows onto the wire. These changes cause foam to break away from behind the slice and to come down with the stock onto the paper making wire, which is very undesirable because where the various bubbles of the foam break, they leave marks on the final product.

It is a well known fact that in the paper industry as well as in other chemical manufacturing industries, foam on a liquid or suspension tends to remove certain chemicals from the liquid and hold them to a higher concentration than that at which they exist in the liquid. In paper manufacture this characteristic is particularly objectionable with respect to dyes. When the foam breaks away and travels on the wire, the high concentration of dye will result in a color streak of higher density than the surrounding paper which, of course, ruins the finished product.

It is particularly necessary in the manufacture of paper to be used for photographic stock that foam streaks be eliminated, and that any imperfections in the surface, due to the concentration

of any material, dye, salt or contaminating substance, be removed because such imperfections are particularly noticeable when such raw stock is coated with a photographic emulsion.

My invention is particularly directed to the provision of a slice which will minimize, if not entirely overcome, imperfections due to the accumulation of foam near a slice on the stuff passing to the making wire.

Coming now to my invention wherein like reference characters denote like parts throughout:

Fig. 1 is a diagrammatic side elevation of portions of a paper making machine equipped with a suction slice constructed in accordance with and embodying a preferred form of my invention.

Fig. 2 is a fragmentary sectional view through a portion of the suction slice shown in Fig. 1, but on a somewhat enlarged scale, the section being taken on line 2—2 of Fig. 4.

Fig. 3 is a top plan view of the suction slice shown in the preceding figures.

Fig. 4 is a section taken on line 4—4 of Fig. 3.

Fig. 5 is a greatly enlarged fragmentary sectional view showing a portion of the suction slice shown in the preceding figures, and taken on line 5—5 of Fig. 2.

Fig. 6 is a fragmentary view showing a modification of the suction device shown in the preceding figures.

Fig. 7 is a section taken on line 7—7 of Fig. 6.

In certain types of paper making machines using a making wire, the stuff 1 is flowed out over a making wire 2 between deckles 3 which may pass around suitable guide wheels 4. In order to control the depth of the stuff 1, it is customary to provide several slices indicated in Fig. 1 as 5 and 6. The slice shown in Fig. 6 is of the well-known variety with which an adjustable board 7 (Fig. 1) is arranged, the elevation of this board being determined by the setting of hand wheels 8 on both sides. The layer of stuff passes beneath the bottom of the board 7 and over the making wire. The slice 5 in accordance with my invention is a suction slice which consists broadly of a tubular member 9 which extends across the machine between the deckle straps and which is slotted at 10 so that foam accumulating on the surface of the stuff may pass through these slots while the major portion of the stuff passes beneath the bottom of the tubular member which serves as a slice.

Inside of the tubular member 9 there is a suction pipe 11 which is preferably connected to a vacuum pump so as to suck the stuff through the pipe 12, the flexible connection 13 and the pipe 55

14 into a white water reservoir 15, pipe 14 ending in a standpipe 16 open at the lower end. In order to evacuate some of the air in the standpipe 16, this is connected by means of the pipe 17 which 5 extends considerably above the making wire 2 at 18 and then passes downwardly through a valve 19 to a pipe 20 which is connected to a suction pump.

As the suction pump is put into operation, the 10 valve 19 can be adjusted to limit the amount of suction placed on the standpipe 16. Foam is drawn from the tubular slice through the pipe 14 and the foam, and a certain amount of water with it, will drop down in the standpipe 16, so that it 15 can be recirculated with the white water 15. One of the objects of having a standpipe 16 is that if the pipe 14 was directly connected to a vacuum pump, the water would get into the vacuum pump, whereas with the arrangement above 20 described, if any water should be drawn upwardly into pipe 17, it will tend to collect and run down in the pipe 17 into the white water vat. However, since the water is considerably heavier than the foam, and since pipe 14 passes around a bend 25 14' in entering the standpipe 16, little, if any, water gets into pipe 17, and by the time this pipe reaches the suction pump, water has been eliminated.

Referring more particularly to Figs. 3 and 4, 30 the tubular slice member 9 is, as above explained, slotted at 10 to receive the foam. It is desirable to preserve the shape of the tubular member, and consequently, I prefer to provide those slots in sections connected by the bars 21, 35 although, if the suction slice is made of heavy enough material, this is not necessary. The tubular slice is supported, as best shown in Fig. 5, at each end by annular members 22 which form plugs fitting the ends of the tubular member 9. These plugs are brazed or welded at 23 to slide members 24 which are mounted to move in suitable tracks 25 carried by the supporting side rails 26. These slide members are adjustable by means of a screw adjustment 27 which can be 40 moved by the hand wheels 28 to vary the height of the two ends of the slice and to control the opening between the slice and the making wire 2 which controls the layer of stuff passing between the deckles 3. It is sometimes desirable to 45 alter the effective height of the bottom edges 29 of the slots 10 without changing the clearance between the bottom of the suction slice and the paper making wire. To do this the tubular slice 9 may be rotated by hand upon the two plugs 22 50 at each end, and when it has been set to the most promising position, it may be fastened by the set screw 30 which extends outwardly from a bracket 31 connected integrally with one of the slide members 24. Usually, after the desired position 55 of the suction slot edges 29 is obtained it is not necessary to continue this adjustment with each adjustment of the height of the slice.

As indicated in Fig. 4, the suction pipe 11, 60 which is carried inside of the hollow slice, is provided with a series of suction apertures 32 extending throughout the length of this pipe. The two ends of the pipe may, as shown in Fig. 5, be supported by inserting them in apertures 33 in the plugs. For some types of work it may be 65 preferable to provide the pipe 11 with elongated slots 34, as shown in Fig. 5, this being particularly true where a certain amount of stuff, as well as foam, collects inside of the tubular slice.

I also contemplate providing a suction slice as 70 shown in Fig. 6, wherein all of the foam and stuff

may be drawn up through a tubular suction member 40 having a partially closed end 41 which terminates in a straight slot 42, leaving an open area 43 for receiving the foam and odd amounts of stuff. If the slice is of the proper diameter, I have found that a pair of these suction pipes 40 at each end is sufficient to remove the material faster than it passes through the slots 10 in the cylinder slice member 9.

It is immaterial just what method is used in 10 removing the water and foam which collects in the tubular slice 9, but it is important that this material should be removed faster than it collects in order to prevent the foam from backing up.

The operation of a machine with a suction slice as above described is practically the same as the standard machines. In starting the formation of paper, the stock is flowed down between the deckle straps and beneath the first slice, 20 which I prefer to make a suction slice, and then passes beneath a second slice which may be of the well known type.

The height of the suction slice can be readily 25 adjusted by hand wheels 28, similar to the hand wheels 8 used in the standard type of slice. However, the movement of these hand wheels causes a tubular member or an open member of suitable shape to move to and from the wire between the deckles. Thus, any foam which tends 30 to collect above the first slice builds up and passes through slots in the hollow slice running down to the bottom of it. Extending along the bottom or close to it is a suction pipe connected with a vacuum line adapted to draw off the foam. Should a sufficient amount of stock run into the 35 hollow slice, the suction pipe will likewise draw off this stuff also.

The arrangement of the machine is such that the foam or the foam and stuff will be drawn 40 off into a white water vat through a standpipe which is connected to a suction pump so that none of the water or particles of moisture reach the suction pump.

I have found that a single suction slice is 45 usually sufficient to remove all difficulties due to foam which ordinarily occurs at the first slice in paper making machines. Since this removal is quite complete, I have not found it necessary to substitute for the second slice also a suction slice 50 of the type described, but there is no reason why this cannot be done if for any reason the stuff should contain a mixture or suspension or solution which is particularly adapted to foam as it reaches the slices of a paper making machine. 55

I have described a preferred embodiment of my invention but it is obvious that the same results could be obtained with a number of different structures. Consequently, I consider as within the scope of my invention all such forms 60 as may come within the scope of the appended claims.

What I claim is:

1. In a paper making machine, the combination with a making wire, of means for flowing stuff out over the wire, means for controlling the width of the flow of stuff on the wire, a combined slice and foam controller comprising a slotted hollow member, closed ends on the hollow member adjacent the means for controlling the width of the flow of stuff, said slotted slice and foam controller including an edge of said slot spaced above the bottom of the hollow member and lying substantially parallel thereto over which foam may flow, a pipe forming a part of the combined 70

- slice and foam controller extending into said slotted hollow member and passing upwardly therefrom, brackets mounted on the machine for adjustably carrying the said combined slice and foam controller for varying the position thereof relative to said making wire, and suction means for removing collected foam through the pipe in any set position of the slice and foam controller.
2. In a paper making machine, the combination with a making wire, of means for flowing stuff out over the making wire, means for controlling the width of the flow of stuff on the wire, a combined slice and foam controller comprising a slotted hollow member, closed ends on the hollow member adjacent the means for controlling the width of flow of stuff, said slice and foam controller including an edge of said slot spaced above the bottom of the hollow member and substantially parallel thereto over which the foam may flow, a pipe forming a part of the combined slice and foam controller extending inside of said slice and foam controller and extending upwardly therefrom, brackets mounted on said machine for adjustably carrying the combined slice and foam controller for varying the position thereof relative to said making wire, and suction means for removing collected foam through said pipe in any set position of said slice and foam controller, said means including a perforated pipe attached to said first mentioned pipe and a support for said perforated pipe in the hollow slice and foam controlling member the perforations of said perforated pipe being positioned below said edge of the slot in said hollow slice and foam controlling member whereby foam passing through said slot may be drawn out by suction through the perforations in the pipe lying inside of the slice and flow controller and may pass therefrom through the pipe leading away from the slice and flow controller.
3. In a paper making machine, the combination with a making wire, of means for flowing stuff out over the wire, means for controlling the width of the flow of stuff on the wire, a combined slice and foam controller comprising a slotted hollow cylindrical member, closed ends on which the hollow slotted cylindrical member is mounted, said ends lying adjacent the means for controlling the width of the flow of stuff, said slotted slice and foam controller including an edge of said slot spaced above the bottom of the hollow cylindrical member and substantially parallel thereto through which foam may flow, a pipe extending to and from said hollow cylindrical member extending inside of the hollow cylindrical member and below the slot therein and forming a part of the combined slice and foam controller, brackets supported on the machine for adjustably carrying the combined slice and foam controller and for varying the position thereof relative to said making wire and suction means for removing collected foam through the pipe in any set position of the slice and foam controller, and means for holding the cylindrical flow controller in a set position relative to the closed ends for holding said slot in a fixed relation to the bottom of the cylindrical slice and foam controlling member.
4. In a paper making machine, the combination with a making wire, of means for flowing the stuff out over the wire, means for controlling the width of the flow of a stuff on the wire, a combined slice and foam controller comprising a slotted hollow member, closed ends for the hollow member adjacent the means for controlling the width of the flow of stuff, said slice and foam controller slot including an edge spaced above the bottom of the hollow member and substantially parallel thereto over which foam may flow, a pipe extending into said hollow member below the slot therein and extending away from said hollow member, brackets mounted on the machine for adjustably carrying the combined slice and foam controller by means of the closed ends for varying the position thereof relative to said making wire, and suction means for removing collected foam through the pipe in any set position of the slice and flow controller, said adjustable brackets fixedly carrying said closed ends, said closed ends having a cylindrical cross section and being adapted to movably support said combined slice and foam controller, and a set screw for holding said cylindrical flow and foam controller in a fixed position upon said cylindrical ends, whereby the slot edge may be spaced above the bottom of said slice and flow controller in different positions by turning said cylindrical flow and foam controller into different positions with respect to said cylindrical ends.

KENNETH J. MACKENZIE.
